CLAIM

The ornamental design for a tire changer press arm foot as
shown and described.

DESCRIPTION

FIG. 1 is a top perspective view of a tire changer press arm
foot;

FIG. 2 is a bottom perspective view of the tire changer press
arm foot;

FIG. 3 is a top view of the tire changer press arm foot.

FIG. 4 is a bottom view of the tire changer press arm foot;

FIG. 5 is left side view of the tire changer press arm foot;

FIG. 6 is right side view of the tire changer press arm foot;

FIG. 7 is a front view of the tire changer press arm foot; and,

FIG. 8 is a rear view of the tire changer press arm foot.

The broken lines shown within the drawings illustrate fea-

tures that form no part of the claimed design.
